UNITED STATES PATENT OFFICE.

THOMAS BERTRAND WILKINSON, OF LOS ANGELES, CALIFORNIA.

OIL-GUN.

No. 928,351.

Specification of Letters Patent.

Patented July 20, 1909.

Application filed November 2, 1907. Serial No. 400,416.

To all whom it may concern:

Be it known that I, THOMAS B. WILKINSON, of Los Angeles, in the county of Los Angeles and State of California, have invented a new and Improved Oil-Gun, of which the following is a specification.

This invention, which relates generally to improvements in oilers, more specifically has for its object to provide a simple, inexpensive and easily manipulated device for "shooting" or squirting lubricant oil, and it refers more particularly to improvements in that type of oiling devices in which a finger pressed plunger is provided, that is automatically moved in one direction for drawing in a charge and finger pressed for ejecting the said charge through the nozzle end.

My present invention comprehends an improved construction and arrangement of cylinder contained pump device and certain combination of parts, all of which will be first described in detail and then be specifically pointed out in the appended claims, reference being had to the accompanying drawings, in which:

Figure 1, is a perspective view of my invention and illustrating the manner it is manipulated for ejecting or "shooting" the lubricant. Fig. 2, is a longitudinal section thereof partly in side elevation, the plunger being at its upper or normal position. Fig. 3, is a similar view of the lower end and showing the position of the ball valve when the plunger is moved to its downward or ejecting position.

In its practical arrangement, my present invention comprises a main cylinder or oil holder 1, having an internally threaded tubular boss 10 at its lower end that extends inwardly from the bottom 11 and which communicates with the outwardly projected and internally threaded boss 12, to which is detachably connected the threaded end 20 of the ejector tube or nozzle 2, in which is located the ordinary type of back check ball valve 21 as clearly shown in Figs. 2 and 3.

3 designates a tubular member or supplemental cylinder that is much smaller than the cylinder 1 and whose lower end 30 is externally threaded as at 31, for screwing into the boss 10 of the main cylinder or reservoir, into which it can be readily fitted by inserting the said tubular member 3 through the open end of the cylinder 1, which end is usually closed by a screw cap 4 that is also formed with a tubular and outwardly ex-

tended central boss 40, provided with a fine internal thread for receiving a stuffing box or gland 5, as clearly shown in Fig. 2. A cap 4 is also provided with oppositely disposed rings 41 with which the fingers of the operator engage during the act of pressing down the plunger rod head 6 with the thumb, as will be clearly understood from Fig. 1 of the drawings.

The pump cylinder or tube 3 at the lower end has an inlet 32 that communicates with a laterally extending valve chamber 33 which has an inlet 34 that is usually in open communication with the inlet 32 and which is closed by a ball valve 35 contained in the chamber 33 when pressure is applied to the plunger rod 60 that carries a pump piston 61 at its lower end and which travels within the tube or supplemental cylinder 3. The piston 61 is formed by fitting two cup shaped leather members 62—62^a back to back, and clamping same between two metal disks 63—63^a that are carried on the lower end of the plunger or piston head 60 as is clearly shown in Fig. 3. The piston or plunger rod 60 passes up through the open end 35 of the pump cylinder or tube 3 and is automatically forced upwardly by a coil spring 7 under it, that is mounted in the lower end of the cylinder 3 and to hold the piston from being forced too far forward and out of the cylinder 3, a stop pin 8 is fixedly mounted on the rod 60 for engaging the upper or cap end of the main cylinder.

By reason of constructing and co-operatively joining the several parts in the manner shown and described, the complete appliance can be economically made and the several parts readily assembled for use and arranged for being readily taken apart, since all that is necessary to separate them is to unscrew the main cylinder cap which will permit of conveniently pulling out the pump piston and rod, after which if desired, the pump cylinder and its valve casting can be quickly disconnected from the main cylinder.

By forming the valve chamber laterally of the pumping cylinder in the manner shown, a simple but positively acting fluid flow controlling means is provided. By having the pump cylinder open at the top the said pump cylinder is at all times filled, irrespective of the position of the piston.

It will be understood that the length of

the pump cylinder or tube 3 in practice is only long enough to allow for the necessary stroke of the piston.

Having thus described my invention, what I claim and desire to secure by Letters Patent, is:—

1. An oiler of the character described, which comprises a main cylinder or reservoir having a discharging nozzle at one end, a tubular member within the cylinder connected with the nozzle end and in direct communication with the nozzle, said tubular member having an inlet at the nozzle end, a valve chamber external of the tubular member having an inlet normally in communication with the inlet to the tubular member, a valve contained in the said chamber adapted under fluid pressure from the tubular member to close off the valve chamber inlet, a piston in the tubular member having a rod that slidably projects through that end of the cylinder or reservoir opposite the nozzle end and a spring for normally forcing the piston and its rod 25 to its uppermost or normal position, as set forth.

2. The combination with the main cylinder or reservoir, having an ejecting nozzle at one end and centrally apertured closure cap at the other end, the nozzle end having an inwardly extended, internally threaded boss; of the supplemental cylinder or tubular member, having its lower end threaded to engage the threaded boss on the main cylinder, a valve chamber on the lower end of the tubular member having an inlet and an outlet, the latter opening into the tubular member, a ball valve within the valve chamber, a piston operable in the tubular member having its rod projected through the aperture in the cap of the main cylinder and a spring in the lower end of the tubular member for forcing the piston normally upward.

45 3. The combination with the main cylinder having a discharging nozzle at one end and a removable centrally apertured cap on the other end; of an ejecting means adapted for being detachably mounted in the main cylinder, said means comprising a tubular member for engaging the nozzle end of the

main cylinder for communication with the ejecting nozzle, a piston spring actuated for its injecting movement and having a rod that projects through the cap of the main cylinder for being finger pressed to move the piston for ejecting the fluid through the nozzle, the tubular member having a single inlet at its nozzle end and a single automatically acting valve for controlling the opening and closing of said single inlet, as set forth.

4. The combination with the main cylinder having a discharging nozzle at one end and an apertured cap at the other end, said cap having a pair of oppositely disposed finger gripping members, the said main cylinder having an internally threaded boss projected inwardly from the nozzle end; of the tubular member 3 having a threaded lower end for engaging the threaded boss on the main cylinder, an inlet at the threaded end, and a valve chamber over said inlet, said chamber having an inlet, a ball valve in the chamber, a piston operable in the tubular member, a piston rod therefor that projects through the apertured cap, a stop washer on the said rod and the coiled spring located in the tubular member below the piston therein, all being arranged substantially as shown and for the purposes described.

5. An oil gun, that comprises a main cylinder, a discharging nozzle at one end thereof, a head at the other end of the cylinder having a finger grip, a tubular member within the cylinder that extends inwardly from the nozzle and is in direct communication with the said nozzle, said tubular member having an automatic valve controlled inlet that communicates with the main cylinder, a piston that operates in controlled inlet that communicates with the main cylinder, a piston that operates in the tubular member, said piston being spring forced in one direction and a plunger for the piston that extends through the head having the finger grip.
